NECKTIE

William Tait, Wyomissing, Pa., assignor to Tait
Hosiery Mill, Inc., Reading, Pa., a corporation of Pennsylvania

Application July 19, 1949, Serial No. 4,002

Term of patent 14 years

(Cl. D3—16)

To all whom it may concern:

Be it known that I, William Tait, a citizen of the United States, residing at Wyomissing, Pa., have invented a new, original, and ornamental Design for a Necktie, of which the following is a specification, reference being had to the accompanying drawing, forming part thereof.

Fig. 1 is a front elevational view of a necktie embodying the design.

Fig. 2 is a reduced plan view showing the outline of the necktie.

The knit shown in Fig. 1 extends throughout the length of the necktie.

I claim:

The ornamental design for a necktie, as shown and described.

WILLIAM TAIT.
